(57) **CLAIM**

The ornamental design for a mounting bracket, as shown and described.

DESCRIPTION

FIG. 1 is a top perspective view of a mounting bracket showing my new design;

FIG. 2 is a bottom perspective view thereof;

FIG. 3 is a top plan view thereof;

FIG. 4 is a bottom plan view thereof;

FIG. 5 is a front elevation view thereof;

FIG. 6 is a rear elevation view thereof;

FIG. 7 is a left side elevation view thereof; and,

FIG. 8 is a right side elevation view thereof.

Dashed lines in FIGS. 1-4, 7 and 8 illustrate unclaimed apertures of the mounting bracket and form no part of the claimed design.

1 Claim, 8 Drawing Sheets
